UNITED STATES PATENT OFFICE.

GERGELY SZÜCS AND STEPHEN KOVACH, OF LOWELL, MASSACHUSETTS.

NON-REFILLABLE BOTTLE.

1,161,359.

Specification of Letters Patent. Patented Nov. 23, 1915.

Application filed February 25, 1915. Serial No. 10,578.

To all whom it may concern:

Be it known that we, GERGELY Szücs, a subject of the King of Hungary, and STEPHEN KOVACH, a citizen of the United States, residing at Lowell, in the county of Middlesex and State of Massachusetts, have invented new and useful Improvements in Non-Refillable Bottles, of which the following is a specification.

10 This invention relates to improvements in devices for preventing the refilling of bottles, jars or the like and has for its object to provide a simple and positively operating device which will not only close the bottle 15 when the same is in an upright position, but will also act to close said bottle when the same is inclined or in a horizontal position.

The invention consists in the combination and arrangement of parts whereby the above 20 object and certain other objects hereinafter appearing may be attained, as set forth in the following specification and particularly pointed out in the claims.

Referring to the drawings: Figure 1 is a 25 section, partly in elevation, of a device embodying our invention. Fig. 2 is a section taken on line 2—2 of Fig. 1. Fig. 3 is a section taken on the line 3—3 of Fig. 1. Fig. 4 is a plan view of the sectional ring. 30 Fig. 5 is a detail view of one of the sections of said ring. Fig. 6 is a detail plan view of the valve.

Like numerals refer to like parts throughout the several views of the drawings.

35 In the drawings, 6 is a bottle and 7 a tubular member which, in the present case, is preferably the neck of the bottle 6 and 8 is the mouth portion of said bottle, the same being of much smaller diameter than the 40 tubular portion 7 and of a length sufficient to contain a cork or any other suitable closure, not shown in the drawings.

A partition 9 is arranged transversely of and adjacent the lower end of the tubular 45 member 7 and is preferably an integral part of said member. An opening 10 is provided at the center of said partition 9 through which all the liquor must pass during the filling or emptying of said bottle. A valve

50 11 is arranged to seat against the upper edge 12 of the partition 9 surrounding the opening 10, said edge being ground to conform to

a correspondingly ground under face 13 of the valve 11.

The valve 11 is provided with a fluted or 55 ribbed stem 14, the ribs of which are arranged to fit and slide within the opening 10 of said partition, thus when said valve is moved away from its seat on said partition passages will be provided for conveying 60 or conducting the liquors to and from the interior of the bottle 6.

Placed above the valve 11 and movable longitudinally of the tubular member 7 is a weight 15, preferably in the form of an inverted cone, constructed of any suitable material such as porcelain. Interposed between the weight 15 and the valve 11 are a plurality of segmental shaped members 16, preferably 6 in number, and forming as it 70 were a sectional ring which surrounds the cone shaped weight 15. The upper faces 17 of the members 16 are adapted to conform with and engage the conical surface 18 of said weight. 75

The members 16 are provided at their lower inner portions with bearing surfaces 19 which are adapted to engage a corresponding surface 20 upon the upper side of the valve 11. The weight 15 is provided 80 with a plurality of ribs 21 which extend substantially from the apex of the base of said member and respectively engage said segmental shaped members within grooves 22, 22, each of said members having one 85 groove adjacent the central portion thereof. The upper face 23 or base of the cone is provided with a plurality of radiating grooves 24, 24 all of which are united at the center and extend to the upper edge of said 90 base.

A second partition or baffle 25 is arranged transversely of the tubular member 7 above the weight 15, said partition being constructed of suitable material such as glass 95 or porcelain, preferably the latter. This partition is preferably secured at a predetermined distance above the partition 9 by molding the same into the material forming said tubular member 7, thus preventing any 100 movement thereof.

A series of openings 26, 26 are provided in the partition 25, preferably around the edge thereof. An annular rim 27 is ar-

ranged within the tubular member 7 between the partition 25 and the weight 15 and at a distance above said weight sufficient to permit the necessary movements of said weight during the opening and closing of the bottle. The rim 27 may be constructed of glass, porcelain or other suitable material and is preferably secured to the member 7 before the partition 25 is permanently fixed 10 in its position. The upper face of the rim 27 is concaved as at 28.

During the assembling of the several parts constituting the closure of the bottle, a fine, flexible cord or wire 29 is inserted through 15 a hole 30 in the upper face of the valve 11. Opposite ends of said wire are then threaded through a passage 31 extending from the apex to the center of the base of the conical weight 15. From the base of said conical member the ends of the wire 29 diverge 20 through different holes 26 in the partition 25, thence upwardly around the nose of the bottle. The wire is then drawn taut thereby lifting the valve 11 from its seat together 25 with the weights superimposed thereabove, thus leaving the opening through the partition 9 wide open. The ends of said wire 29 are then secured to the nose of said bottle in any suitable manner, such as by winding 30 a wire about the exterior of said nose, thus holding said valve in its open position. The bottle may then be filled without difficulty and after being filled the wire is withdrawn from the valve 10 by pulling from 35 one end only and said valve is permitted to be closed by the combined weights of the member 15 and the members 16. A slight space 32 is always maintained between the members 16 and these spaces are always 40 maintained in alinement with the grooves 24 by the coöperation of the ribs 21 and grooves 22.

In the normal position of the device, that is upright as shown in Fig. 1, the weight 15 45 coöoperating with the weights 16 maintains the valve closed. To remove the contents of the bottle, said bottle must be inverted until the weights 15 and 16 move away from the partition 9 and against the rim 27, thus the 50 valve 11 will be permitted to open. Should said bottle be tipped to a horizontal position the valve 11 will be maintained closed and in fact said valve will be maintained closed until said bottle has been turned to a 55 point in which the median axial line thereof is inclined at an angle to a horizontal plane, equal to the angle of the side of said cone shaped weight. The base of said bottle is at this time above the horizontal plane. In 60 other words, assuming that the angle of one side of said cone is at 45° to its axis, said bottle may be tipped 135° from the vertical or upright position before said valve will begin to open, or within 45° of its absolutely 65 inverted position. The cause of this is due

to the fact that the segmental sections 16 are constructed in the form of wedges and as said bottle is turned in the direction of the arrow "a" Fig. 1. The weight of the uppermost one of said sections 16 will cause 70 said member to drop and owing to the inclination of the face 17, which coöperates with the inclination of the cone shaped member 15, said member will be forced against the valve 11. The members 16 on 75 the lower half of the sectional ring will be moved against said valve by the weight of the sections above together with the weight of the member 15, which during the inverting of the bottle will be moved against the 80 rim 27.

It must therefore be necessary in order to overcome the tendency to close said valve to move the bottle to a position where the effect of the inclined surfaces 17 and the conical surface 18 will be neutralized. By providing the rim 27 directly beneath the openings 26 and by forming in the upper face of said rim the concavity 28, it will be impossible 90 for a wire to be passed through said openings 26 downwardly around the outer edge of the member 15 and between the adjacent members 16 to the seat of the valve and thus prevent said valve from entirely closing the opening. Furthermore by the use of the 95 weights 16 coöperating with the cone shaped member 15 it will be impossible to turn the bottle upon its side and refill the same, as the valve at this time is maintained absolutely closed.

Having thus described our invention what we claim and desire by Letters Patent to secure is:

1. A nonrefillable bottle having, in combination, a tubular member, a partition extending transversely of said tubular member and provided with an opening, a valve arranged to close said opening, a movable member arranged above said valve, and a series of segmental shaped weights surrounding said movable member and adapted to coöperate with said movable member to close said valve.

2. A nonrefillable bottle having, in combination, a tubular member, a partition extending transversely of said tubular member and provided with an opening, a valve arranged to close said opening, a movable member arranged above said valve, and a series of segmental shaped weights surrounding and interlocking with said movable member and adapted to coöperate with said movable member to close said valve.

3. A nonrefillable bottle having, in combination, a tubular member, a pair of partitions disposed transversely of and within said tubular member and at a substantial distance apart, each of said partitions being provided with an opening, a valve adapted to close the opening of one of said parti- 130

tions, an inverted cone shaped member arranged intermediate said partitions, and a series of segmental shaped weights arranged about and in contact with said cone shaped member and adapted to coöperate therewith to maintain said valve closed.

4. A nonrefillable bottle having, in combination, a tubular member, a partition extending transversely of said tubular member and provided with an opening, a valve arranged to close said opening, a movable member arranged above said valve, means for limiting the movements of said movable member away from said partition, and a series of segmental shaped members arranged about and in contact with said movable member, said segmental shaped members being constructed and arranged to coöperate with said movable member to maintain said valve closed.

5. A nonrefillable bottle having, in combination, a tubular member, a partition arranged within and transversely of said tubular member, said partition being provided with an opening, a valve adapted to close said opening, an inverted cone shaped member arranged in said tubular member above said valve, a series of ribs extending substantially from the apex to the base of said cone shaped member, and a series of segmental shaped members arranged about said cone shaped members, each of said segmental shaped members having a groove adapted to receive one of said ribs, said cone shaped member and said series of segmental shaped members being constructed and arranged to maintain said valve closed.

6. A nonrefillable bottle having, in combination, a tubular member, a partition arranged within and transversely of said tubular member, said partition being provided with an opening, a valve adapted to close said opening, a weight arranged above said valve to move longitudinally of said tubular member, means to limit the movements of said weight away from said valve, and a series of segmental shaped wedges arranged above said weight adapted to coöperate therewith to maintain said valve closed.

7. A nonrefillable bottle having, in combination, a tubular neck portion, a partition arranged within and transversely of said neck, said partition having a central opening, a valve constructed and arranged to seat on said partition and to close said opening, an inverted cone shaped member arranged above said valve and movable longitudinally of said neck, means for limiting the movements of said cone shaped member away from said valve, a series of segmental shaped wedges surrounding said cone shaped member and engaging said valve, said wedges being separated from each other by spaces, said cone shaped member having a plurality

of radiating grooves alining with said spaces, and means to retain said spaces and said grooves in said alinement.

8. A nonrefillable bottle having, in combination, a tubular neck portion, a mouth portion substantially smaller in diameter than said neck, a partition arranged within and transversely of said neck, said partition having a central opening, a valve constructed and arranged to seat on said partition and to close said opening, an inverted cone shaped member arranged above said valve and movable longitudinally of said neck, means for limiting the movements of said cone shaped member away from said valve, a series of segmental shaped wedges surrounding said cone shaped member and engaging said valve, said wedges being separated from each other by spaces, said cone shaped member having a plurality of radiating grooves alining with said spaces, and means to retain said spaces and said grooves in such alinement.

9. A nonrefillable bottle having, in combination, a tubular member, a pair of partitions disposed transversely of and within said tubular member and at a substantial distance apart, each of said partitions being provided with an opening, a valve adapted to close the opening of one of said partitions, an inverted cone shaped member arranged intermediate of said partitions, a series of segmental shaped weights arranged about and in contact with said cone shaped member and adapted to coöperate therewith to maintain said valve closed said cone shaped member having a hole extending from the center of the base to the apex thereof, said valve having a transverse hole adjacent to the top thereof, and a flexible member adapted to be passed through the holes in said partitions, said cone shaped weight and said valve, adapted to elevate and hold said valve away from said partition whereby said bottle may be filled.

10. A nonrefillable bottle having, in combination, a tubular member, a partition extending transversely of said tubular member and provided with an opening, a valve arranged to seat against said partition and close said opening, a stem for said valve having slidble engagement with said partition within said opening and adapted to guide said valve, said stem having a plurality of grooves extending longitudinally thereof, and a plurality of segmental shaped weights arranged in a continuous series around and above said valve and adapted to coöperate during the inclination of said bottle to maintain said valve in contact with its seat.

11. A nonrefillable bottle having, in combination, a tubular member, a partition extending transversely of said tubular member and provided with an opening, a valve arranged to close said opening, a movable
